UNITED STATES PATENT OFFICE.

CHARLES B. PERRIGO, OF BLOOMINGTON, ILLINOIS.

POCKET CHECK-BOOK.

SPECIFICATION forming part of Letters Patent No. 231,497, dated August 24, 1880.
Application filed June 19, 1880. (No model.)

To all whom it may concern:

Be it known that I, CHARLES B. PERRIGO, of Bloomington, in the county of McLean, and in the State of Illinois, have invented certain new and useful Improvements in Pocket Check-Books; and I do hereby declare that the following is a full, clear, and exact description thereof, reference being had to the accompanying drawings, and to the letters of reference 5 marked thereon, making a part of this specification, and in which—

Figure 1 represents a perspective view of my improved check-book when open; Fig. 2, a plan view; showing the manner of arranging 15 the checks with their stubs, the upper check and stub being broken away to show the lower one.

My invention relates to certain new and useful improvements in check-books; and the invention consists in a novel arrangement of 20 checks and stubs that, when folded together, will form a check-book which can be conveniently carried in the pocket, all as will be hereinafter fully described, and specifically pointed 25 out in the claim.

In the drawings, A represents my improved check-book, composed of a series of checks, a, and alternate check-stubs b.

In forming the book A, I use the ordinary 30 blank check with stub connected at one end, and having a transverse row of perforations, c, by which the check can be readily removed or torn from the stub. These checks and stubs are arranged in pairs, with one check and stub 35 face up and the other face down and reversed, so that the stub of one check projects over the next check, all as clearly shown in Fig. 2. This arrangement is continued until the book is finished. The checks and stubs are then secured

together in the usual and well-known manner 40 and folded on the dotted line x, after which the cover d is applied.

By the above-described arrangement of checks and stubs they alternate with each other throughout the entire book, so that in opening 45 it to fill out a check the check will always be face up on the right-hand side and the stub face up on the left-hand side of the book.

I am aware that a check-book provided with stub-sheets having stub-blanks on both sides 50 thereof secured between alternate pairs of two separate check-sheets is old, and also a book consisting of alternate stub and check leaves is old, and such I do not wish to be understood as claiming, broadly, as of my invention. 55

Having thus fully described my invention, what I claim as new, and desire to secure by Letters Patent, is—

The herein-described pocket check-book, composed of the ordinary checks with attached 60 stubs, said checks, with their attached stubs, arranged in pairs, with one check and its stub face up and the other face down and reversed, with the stub of one check projecting over the next check, the checks and their stubs bound 65 together and folded, whereby the checks and stubs alternate throughout the book, with the check always face up on the right-hand and the stub face up on the left-hand side of book when opened to fill up a check, as specified. 70

In testimony that I claim the foregoing I have hereunto set my hand this 11th day of May, 1880.

CHARLES B. PERRIGO.
